(57) **CLAIM**

The ornamental design for a toothbrush, as shown and
described.

DESCRIPTION

FIG. 1 is a perspective view of the toothbrush;
FIG. 2 is a front view of the toothbrush;
FIG. 3 is a back view of the toothbrush;
FIG. 4 is a side view of the toothbrush, the opposite side
being a mirror image thereof;
FIG. 5 is a handle end view of the toothbrush; and,
FIG. 6 is a brush end view of the toothbrush.
The toothbrush comprises a brush configured on a brush end
and a handle having a plurality of protrusions.
